United States Patent Office

Des. 183,413
Patented Aug. 19, 1958

183,413

SOFA

Forest Wilson, Chicago, Ill.

Application May 1, 1956, Serial No. 41,287

Term of patent 14 years

(Cl. D15—11)

FIG. 1

FIG. 2

FIG. 3

FIG. 4

Fig. 1 is a perspective view of the sofa embodying my new design;

Fig. 2 is a left-hand end view of the sofa of Fig. 1;

Fig. 3 is a front view of the sofa of Fig. 1; and

Fig. 4 is a top view of the sofa of Fig. 1.

I claim:

The ornamental design for a sofa, substantially as shown.
